to Aeret Air Conditioner Company, a corpora-
tion of Illinois

Application July 14, 1933, Serial No. 680,439

11 Claims. (Cl. 261—115)

This invention relates to air conditioners, and has as its primary object to provide a heating, cooling, humidifying and dehumidifying conditioning unit of such compactness that it may be 5 installed in an ordinary living room.

One aspect of the invention is the arrangement of a blower in an upright, elongated casing so as to draw air through a spray chamber which is almost co-extensive in area with the front of 10 the casing, i. e., extends across the casing in a plane parallel to the two major dimensions of the casing, whereby to give a maximum water contact in a casing of minimum volume.

Another aspect of the invention is the discovery that, in such an arrangement, it is possible 15 to pass a stream of air having a cross sectional area corresponding to the major dimensions of said spray chamber through a spray traversing the entire chamber, and thence directly into the blower, without carrying moisture, an eliminator screen interposed between the spray and the blower and almost in contact with them both, serving effectually to remove liquid particles from 20 the air before it reaches the blower.

An object is to provide means whereby the 25 spray chamber may occupy a quite shallow space co-extensive with the inlet of the casing, such means comprising chiefly a pair of air porous screens mounted in said inlet in closely spaced 30 positions parallel to the front of the casing, the outer screen serving to prevent water splashing out of the casing, and the other being the eliminator above mentioned.

A further object is to provide a novel method 35 of securing a maximum water contact with a moving air stream, said method involving the production of a plurality of sprayed sheets of fine water particles, the respective sheets being spaced just far enough apart to insure the spacing of 40 the individual water droplets, and passing the air stream transversely through said sheets.

Another object is to provide a novel spray im- 45 peller for producing the aforementioned closely spaced plural sheets.

It is the purpose to provide in combination with 50 a conditioning unit having air moving and water spraying means as aforesaid, an arrangement of a water cooler, and a supply line from a water main, either of which may be used for feeding the spray, the cooler being used for extreme conditions of heat and humidity and the supply water being used for humidification in cold weather.

Another object is to provide an arrangement 55 for collecting the spray water, returning it to the cooler when the latter is being used, or returning

it to the spray when the device is being used for humidification. This embodies the use of a collecting pan below the spray, a valved return from the pan to the cooler, and a pump communicating with the pan and with the spray. 5

A further object is to provide an arrangement whereby both the return pump and the supply line may be in operative connection with the spray impeller at the same time, means being provided to prevent backflow of water from the supply line through the pump. 10

Another object is to provide an arrangement whereby the supply line may serve only as a replenishing medium when the conditioner is being used for humidifying, a float valve being provided for cutting off the supply line just below the level of the top of the collecting pan. 15

Another object is to provide means whereby 20 said float valve may be rendered inoperative to the extent that a constant flow of water may be allowed to pass by the float valve for cooling and dehumidifying purposes, this being accomplished by opening a by-pass overflow which controls a water level below the level controlled by the float valve, and yet does not interfere with 25 the functioning of the float valve as a safety means to prevent the water level reaching the top of the pan.

It is also our object to avoid the building up 30 of the water level by water condensed from the air when the system is used with the cooler circuit in operation, whereby a maximum percentage of the circulating water may be retained in the cooler to secure maximum cooling effect.

Another object is to provide a conditioner in 35 which access to the interior is facilitated by the removability of the screens and the resting of the conditioner casing in the water pan without attachment thereto.

Another object is to utilize the water sealing of 40 the lower extremities of the screens and the casing in the collecting pan to cause the entire air stream to pass through the screens.

With these and other objects in view our invention consists in the combination and construction and arrangement of the various parts thereof, whereby the objects contemplated are attained, as more fully set forth in the accompanying specifications, pointed out in the claims, and illustrated in the accompanying drawings, in 45 50 which:

Fig. 1 is a front elevation of the conditioning system, the cooler being shown in diagram and parts of the conditioning unit being broken away to illustrate the operating mechanism therein. 55

Fig. 2 is a vertical sectional view of the conditioning unit, and

Fig. 3 is a detail sectional view of the check valve and feed connection to the spray impeller.

5 Fig. 4 is a detail sectional view of the impeller and pump gearing, and the eliminator screen.

Fig. 5 is a detail sectional view of the pump and impeller transmission.

Fig. 6 is a sectional view showing the blower 10 unit in end elevation.

Fig. 7 is a detail view of the damper control, and

Fig. 8 is a piping diagram showing a slight 15 modification of the system wherein the cooler is above instead of below the conditioning unit.

The conditioning system comprises generally a 20 conditioning unit A, a supply line B connected to a water main, and a water cooler C. The latter will comprise the conventional combination of heat absorbing means acting to cool a water 25 circulating circuit including the intake and discharge connections 10 and 11, and a suitable pump E for circulating the cooled water through the conditioning unit A and back to the cooler. Being conventional, these parts are not illustrated in detail.

A cabinet or hood D encloses the conditioning unit A and is provided with front and top grilles 12 and 13, substantially the entire area of both 30 front and top being open to allow free circulation to and from the unit A.

The casing of the unit A includes upper and lower sections 14 and 15, joined in a horizontal plane 16 by marginal flanges 17 and 18 bolted 35 together by bolts 19.

The respective sections 14 and 15 include end walls 20, 20a connected by the respective rear walls 21, 21a.

The liquid contact chamber N is positioned 40 parallel to and closely adjacent the front of the conditioner casing, extends the full length of the casing, and extends vertically a major portion of the height thereof, being spaced from the top wall 22 of the casing to provide a heated air outlet O and separated therefrom by a partition 23 45 extending from end to end of the casing and secured to the end walls 20 as by means of flanges 24 welded to the walls 20.

The heating element 30 is mounted rearwardly 50 of the top of the contact chamber N, being spaced from the rear wall 21 of the casing so as to form a cooled air outlet Q. A plate 25, secured to the rear edges of the fins of the element 30, forms the forward wall of the outlet Q.

55 A deflector wall 26, formed as a downwardly and rearwardly inclined continuation of the top wall 22, meets the plate 25, to deflect all air passing upwardly through the element 30, forwardly through the outlet O.

60 An upstanding baffle 27, formed as a continuation of the rear extremity of the partition wall 23, forms with the plate 25 a heating passage P in which all of the blower discharge may be constrained to contact the element 30. The baffle 27 65 also serves, by the spacing of its upper edge above the lower extremity of the outlet O, to cause a concentration of the air stream against the deflector wall 26 which will result in a decided downward inclination of the air stream leaving the outlet O, so as to overcome the effect of the buoyancy of the heated air and to prolong the horizontal travel of the discharged air stream. The upper wall 22 is given a downward cant to 70 correspond to the direction of discharge and to assist in the downward bending of the discharge. 75

All of the walls 22, 23, 25, 26, and 27 extend full length of the casing, the walls 22, 23, 26 and 27 being secured to the end walls 20 as indicated, to rigidify the upper portion of the casing.

The blower R occupies the lower portion of the 5 space behind the contact chamber N, being of less height than the chamber so as to leave, between its upper level and the level of the top of the contact chamber, a space S in which the blower discharge may be diverted either to the 10 heating passage P or to the cooled air outlet Q. The forward extremity of the space S is defined by a partition wall 28, secured to the partition wall 23 as at 29 and inclined rearwardly and downwardly from the top of the contact chamber 15 N to the blower outlet 105 and resting in contact with the top plate 30 of the blower unit without being secured thereto. A damper 31, swingingly mounted on an axis close to the lower rear corner of the element 30, may be swung from the full 20 line position shown to the dotted line position p. In its full line position it directs the blower discharge to the cooled air outlet Q. In its dotted line position, it directs the blower discharge to the heating passage P. An operating lever 32 25 (Fig. 7) has one end bent at right angles as at 33, extended through an opening in the end wall 20, and secured to one end of the damper 31 to form one of the pivots on which the damper is swung. The lever 32 cooperates with a notched keeper 34 30 to retain the damper in either of its adjusted positions. The lower edge of the damper is provided with a sealing strip 35 which is adapted to contact either the partition wall 28 or the rear wall 21a, its primary function being to prevent 35 rattling of the damper against said walls under any vibration that the operating parts of the conditioner may set up. Both damper 31 and partition wall 28 extend full length of the casing.

The casing is open at the front with the exception of a trough 36 and an apron 37 depending therefrom, both extending from end to end of the casing, and supported by attachment of the ends of the trough to the end walls 21a, the trough thus serving as a bracing strut connecting the 45 lower forward corners of the end walls. Channels 38 are formed at the sides of the trough 36, to receive the screens 39, 40, which define the water contact chamber N, substantially co-extensive with the open front of the casing. 50

The partition wall 28 serves the additional function of deflecting the air drawn through the chamber N down to the blower R, whereby the velocity of the air as it passes through the chamber N may be relatively low because of the large 55 area of the chamber, and may gradually increase as it concentrates toward the blower inlets. The air travel is indicated by the arrows 41.

As the air travels through the chamber N, it is cut by a plurality of closely spaced sheets of 60 fine water droplets, discharged tangentially from a plurality of conical disks 42 forming part of the spray impeller. The velocity of the discharged water particles is such as to resist the deflecting action of the air stream until they contact the 65 periphery of the chamber N defined by the trough 36 and a spacing flange 43 which extends around the top and ends of the chamber. From the periphery of the chamber the water particles will splash in all directions, disintegrating to form 70 even finer droplets which will thoroughly wet the inner surfaces of both screens 39 and 40.

The narrowness of the chamber N not only insures the thorough wetting of the screens, but prevents the water particles acquiring from the 75

air stream sufficient velocity in the direction of air flow to be impelled through the inner screen 40, which serves as an eliminator.

Thorough enough elimination to allow the blower and other operating parts to be positioned directly adjacent the eliminator screen, is secured through the above noted narrowness of the chamber N and the use of a screen comprising a mat 44 of spun glass, encaged between grids 45 of wire cloth or perforated metal and framed in a channel 46. The mat 44 is impregnated with latex, forming a coating which bonds together the individual glass fibres where they cross each other, without impairing the air porosity. This bonding gives support to the fibres to prevent settling of the mat under its own weight when carried in an upstanding position. It also cushions the fibres against the jars of handling.

The forward screen 39 serves to prevent splashing of the water out of the front of the casing.

The spacer 43 is secured to the forward screen 39 and a spacing flange 47, also extending around three sides of the chamber N, is secured to the inner screen 40. The overlapping of the flanges forms an effective seal to prevent passage of air or water around the edges of the screen 40 from the chamber N. The inner screen 40 is positioned by the channel 38 and a strip 48 secured to the partition 23 and engaging the top of the screen 40 from the rear. The two screens are spaced from each other by the spacers 43, 47. They are both held in position by a removable strip 49 attached by bolts 50 to the partition 23, and may be removed by removing the strip 49, tilting them forwardly, and lifting them from the channels 38.

The casing is open at the bottom and rests in a collecting pan 51 without attachment thereto. Water is collected between the screens by the trough 36, passes through drain openings 52, and is conveyed by a drain skirt 53 to the body of water in the pan 51, the skirt 53 serving to avoid splashing noises which would be caused if the water were allowed to drip.

The apron 37 prevents passage of air below the screens, serving, in conjunction with the end walls 20a and rear wall 21a of the casing to effect a water seal in the body of water in the pan.

The blower unit R comprises a base frame 54, a pair of blower housings 55, mounted thereon as by means of legs 56, an electric motor 57 mounted on the base frame through the medium of a resilient mounting 58, and fans 59 mounted, in the housings 55, on the motor shaft 60. The side walls 55a, 55b of the housings 55, are attached by flanges 61 to the top plate 30, in which outlet openings 105 are formed to register with the mouths of the housings 55.

Bridging the space between the housings 55, and secured to the flanges 61, of the adjacent side walls 55b, are supporting bars 62 from which is suspended on screws 63, and cushioned by rubber washers 64, the impeller bracket 65. The bracket 65 is formed with a nozzle defined between a shaft bearing 66 and a spaced co-axial encircling sleeve 67 which merges into a laterally extending supply connection 68. The impeller shaft 69 is journalled in the bearing 66. The impeller drum 70 has a hub 71 mounted on the shaft 69 and engaging the end of the bearing 66 to prevent axial movement of the impeller toward the bracket 65. A pulley 72, secured to the other end of the shaft, engages the other end of the bearing 66 to prevent axial movement of the impeller away from the bracket.

The impeller disks 42 are centrally apertured

to snugly receive the drum 70, and are secured between a flange on the forward end of the drum 70 and a collar 73 threaded on the rear end of the drum. The collar 73 snugly encircles the nozzle sleeve 67 with just enough clearance to rotate freely. The disks 42 are spaced apart by radial, fluted darts 74 formed in their central regions, the flutes being pointed so as to merge with the rim of the disks as shown. Openings 75 in the drum 70 provide communication from the interior of the drum to spaces between the disks 42.

To the connection 68 is attached a T connection 76 (Fig. 3), through the medium of a nipple 77. The connection has the coaxial opposed branches 78 and 79. Into the former is threaded a sleeve 80 carrying a nipple 81. In the branch 79 is mounted a nipple 82 which projects into the connection 76 to form a valve seat. A check valve element including a pilot skirt 83 axially slidable in the nipple and a valve head 84, seats against the nipple 82 when pressure in the nipple 81 exceeds that in the nipple 82.

To the nipple 81 is attached a tube 85 leading from a common connection 86 to the water supply main B and the cooler discharge pipe 11. To the nipple 82 is attached a tube 88 leading from the collecting pan pump 89. When the conditioner is using water from the main B, the check valve will close off the tube 88 to prevent back flow of water through the pump 89, which would occur in the absence of a check valve due to greater pressure being supplied by a water main than will be developed by the pump 89. Such back flow would cause a pressure loss resulting in decreased effectiveness of the spray.

The supply of water from the main B may be shut off by a hand valve 90 so as to allow only the pump 89 to supply collected pan water to the impeller. This will occur when the system is used for cooling and dehumidifying. The refrigerated water from the cooler C will gather water of condensation from the air which it conditions, and will thus need no replenishing from the main B. In this case, there will be a closed circuit connecting the cooling and conditioning units, cooled water being pumped from the cooler C through the pipe 11, the connection 86, the tube 85 and the connection 76 to the impeller, collected by the pan 51 and returned through the outlet 91 to the return pipe 10 and thence back to the cooler C. It is desirable that the level of collected water remain low during this operation, so that most of the body of water may remain under the refrigerating effect of the cooler C.

The tube 85 communicates with the connection 86 through a float valve 92, which will close at a level near the top of the pan 51. This valve automatically regulates the replenishing of water when the conditioner is being used for humidifying, in which case it is desirable that the level in the pan remain fairly high to insure plenty of water for the pump 89, to supply water to the spray for humidifying. As an added safety measure to insure against overflowing of the pan in the event of failure of the float valve 92, a constantly open overflow 93 is provided, communicating with a drain pipe 94 leading to a sewer or other region of disposal. The overflow 93 controls a level somewhat above that controlled by the float valve 92, whereby under normal conditions the level in the pan during humidifying will be controlled by controlling the inflow of water from the supply line B rather than by disposing of waste water.

When the conditioner is to be used for cooling

and dehumidifying, it becomes necessary that the float valve 92 remain normally open or inoperative so that it will not interfere with the flow of cooled water from the pump E. If the amount of water in the system remained the same, the level in the pan 51 could be set at a level below the level controlled by the float valve 92, thus insuring the latter remaining open. But in dehumidifying, water condensed from the air will gradually add to the water in the system. To overcome this problem, we provide an auxiliary overflow 95, communicating with the drain pipe 94 through a hand valve 96. The level controlled by the overflow 95 is sufficiently above the outlet 91 so as to insure the flow of collected water back to the cooler C when the latter is operating. On the other hand, the level controlled by the overflow 95 is sufficiently below the level controlled by the float valve 92 to insure the latter remaining inoperative when the overflow 95 is open.

When the system is used for humidifying, the valves 96, 97, 97a are closed off, cutting out the cooler C and the overflow 95, and the valve 90 is opened.

25 When the system is used for cooling, the valve 90 is closed off after charging the system with water, and the valves 96, 97, and 97a are opened.

The pan 51 has a moisture collecting eave 98 which is connected by a small tube 99 to the drain pipe 94. Moisture condensing on the exterior of the pan is thus carried away without reaching the floor of the room in which the unit is installed.

30 The impeller extends through an opening 110 in the rear screen 40, which opening is closed by a cap plate 111 pressed onto the nozzle sleeve 67 and against the bracket 65 and engaging the rear face of the screen 40 at its rim.

35 The impeller and pump 89 are driven from the motor shaft 60. A gear casing 112 encloses a helical gear 113 on the shaft 60 and two helical gears 114 and 115 on shafts 116 and 117 mounted at right angles to each other in the casing 112. The gears 114 and 115 mesh with the gear 113. On the end of the shaft 116 is mounted the pulley 45 118, aligned with the pulley 72 on the impeller shaft, and driving it through the medium of a belt 119.

40 On the lower end of the shaft 117 is mounted the operating mechanism of the pump 89. The pump casing is connected to the gear casing 112 by a sleeve 120 which encases the shaft 117.

45 The heating element 30 extends through openings 100 in the end walls 20 of the upper casing section 14 and rests upon the upper edges of the end walls 20a of the lower section 15. The two sections are detachable to allow assembling and removal of the element 30.

50 Steam supply pipes 101 for the element 30 occupy the spaces between the ends of the conditioning unit A and the cabinet D, and connect to the headers 102.

55 In Fig. 8, a slightly modified form of piping hook-up is shown, in which the return 10 is connected to the drain 94 by a pipe 106 in which is a valve 107, which remains closed at all times except when it is desired to drain the cooler.

60 Thermometers 108 and 109 may also be provided, to check inlet and outlet temperatures when the unit is using cooled water.

65 70 In summary, it may be noted that we achieve maximum water contact by drawing air through a contact chamber occupying a major portion of the area of the front of the conditioner casing, passing the air through a highly disintegrated water spray comprising a plurality of closely

spaced sheets of tangentially traveling fine water particles intersecting the air stream at right angles and bouncing back into the air stream in even more finely divided state. By discharging a plurality of sprays, parallel to each other, the entire chamber is completely filled with substantially uniformly spaced droplets, all moving so as to cut the air stream at right angles. This discharge is indicated by the dotted lines 103 in Fig. 3.

75 10 Air travels through the chamber N at relatively low velocity and the distance it moves in traversing the chamber is not sufficiently great for it to impart to the water particles sufficient movement toward the screen 40 to propel the water particles through the screen. Thus the screen may be quite air pervious so as to offer little resistance to the air flow through the chamber. The velocity of the water particles is much higher than that of the air, which further minimizes 15 deflection of the water particles against the screen 40, and maintains the spacing of the plural sheets of water particles through the entire height and length of the chamber.

20 25 We find it possible to obtain compactness in arranging the blower immediately adjacent the eliminator screen, discharging upwardly. We provide for selective upward discharge of cooled air (desirable because it is heavier than the warmer air) in a room being cooled, or projection of a heated air stream below the horizontal to compensate for its buoyancy.

30 35 We provide a system of water supply and disposal which allows the collected water to be used over and over again, or allows a closed circulation through a water cooler, with provision for automatic control of the supply from the main by a float valve when the system is used for humidifying, or rendering the float valve inoperative when a constant flow through it for dehumidifying 40 is desired; and which provides against overflow of the collecting pan under any conditions.

45 50 We claim as our invention:

1. In an air conditioner, a spray impeller comprising a plurality of stacked, coaxial disks provided with radial flutes, a hollow dispensing chamber on which said disks are mounted, a liquid supply nozzle extending axially into one end of said chamber, and a drive shaft on which said chamber is mounted, extending axially 55 through the center of said nozzle.

2. In an air conditioner including a casing through which an air stream is passed, a device for delivering water into contact with said air stream, a water pan to collect said water, a pump 55 for returning water from the pan to the delivery device, a pipe line for conveying water to said delivery device from a supply main, a common connection joining said pump and said line to the delivery device, and a check valve for preventing back flow of water from said connection to the pump.

3. In an air conditioner, a casing, a motor driven blower unit therein, a rotatable spray impeller, a drive connection between said unit and the impeller for rotating the latter, including a shaft, and an eliminator screen through which said shaft extends, interposed between the impeller and the blower unit.

4. In an air conditioning system for dehumidifying and cooling summer air, a conditioning unit including means for delivering water into contact with a moving air stream and a pan for collecting said water, a cooling unit, means to convey cooled water from the cooling unit to said 75

conditioning unit, said last means including a float valve in the aforesaid pan, set to close at a predetermined level of the water in said pan, a return for conveying water from the pan back to the cooling unit, and an overflow for draining water from the pan at a level above the level of the inlet to said return and below the level controlled by said valve, for disposing of water of condensation.

5. In an air conditioner, an upright casing formed with a water contact chamber occupying a major portion of the area of the front of the casing but spaced from the top thereof to provide a heated air delivery outlet, a cooled air outlet in the top of casing at the rear thereof, a blower unit behind said water contact chamber, pulling air through said chamber and delivering it upwardly to said unheated air outlet, a heating element located above said blower, rearwardly of said heated air outlet and forwardly of said unheated air outlet, means to supply a water spray to said contact chamber, means to cool said water whereby the air will be cooled by contact therewith, and adjustable means in the casing for selectively diverting the blower discharge through said heating element, or to said unheated air outlet.

6. In a combination air heater and air cooler, an upright casing, having an opening in one side, a pair of closely spaced parallel filter screens the outer of which traverses said opening, mounted within said casing to form between them a relatively thin water contact chamber, means to spray cooled water in said chamber, a blower between the inner screen and the opposite side of the casing, a delivery chamber being formed in the casing, communicating with the blower outlet, and separated from the contact chamber, heated air and cooled air outlets at opposite corners of the top of the casing, said cooled air outlet communicating with said delivery space, a heating element disposed between said delivery space and said heated air outlet and in communication with both and adjustable means in said delivery space to selectively connect said blower outlet to either said heating element or to said cooled air outlet.

7. In an air conditioner, an upright casing having an opening occupying at least a major portion of the area of one of its upright sides, and a top discharge outlet, a pair of closely spaced filtering screens the outer of which traverses said opening, forming between them a relatively thin

water contact chamber, and a blower disposed between the inner of said screens and the opposite side of the casing, said blower pulling air through said screens and delivering it to said outlet, and means for delivering a spray of water in said chamber, in a plane parallel to said screens and transverse to the flow of the air stream to the blower.

8. In an air conditioner, a casing, a motor driven blower unit therein, a rotatable spray impeller, a drive connection between said unit and the impeller for rotating the latter, including a shaft, and an eliminator screen through which said shaft extends, interposed between the impeller and the blower unit, said impeller being adapted to produce a spray of water particles moving parallel and close to the adjacent face of said eliminator screen, and transverse to the air stream moving through said screen.

9. In an air conditioner, a casing having an inlet opening, a blower in the casing, pulling air through said opening, means to deliver a relatively thin spray comprising a plurality of closely spaced sheets of water particles moving substantially parallel to each other across the air stream moving from said opening to said blower, and an eliminator screen interposed between said blower and said sheet, parallel and closely adjacent to the latter.

10. In an air conditioner, a spray impeller comprising a plurality of stacked, coaxial disks slightly spaced apart, a hollow dispensing chamber on which said disks are mounted, a liquid supply nozzle extending axially into one end of said chamber, and a drive shaft on which said chamber is mounted, extending axially through the center of said nozzle.

11. In an air conditioner, a casing having an inlet opening, a pair of closely spaced screens across said inlet opening, means for projecting a water spray between said screens and substantially parallel thereto at a relatively high velocity, some of the droplets of said spray striking and rebounding from the inner surfaces of the screens to keep said inner surface wetted without passing through the screens, and means for causing a current of air to flow through said inlet opening and through the screens and the spray at a lower velocity than the velocity of said spray.
